UNITED STATES PATENT OFFICE.

JOHN ERICKSON, OF CHICAGO, ILLINOIS, ASSIGNOR TO STROWGER AUTOMATIC TELEPHONE EXCHANGE, A CORPORATION OF ILLINOIS.

TELEPHONE-TRANSMITTER.

SPECIFICATION forming part of Letters Patent No. 787,361, dated April 18, 1905.

Application filed May 4, 1903. Renewed October 3, 1904. Serial No. 227,022.

To all whom it may concern:

Be it known that I, JOHN ERICKSON, a citizen of the United States, residing at Chicago, in the county of Cook and State of Illinois, have invented a new and useful Telephone-Transmitter, of which the following is a specification.

My invention relates to telephone-transmitters; and my object is to produce a simple construction which is particularly sensitive to the action of sound-waves, yet is not easily rendered inoperative by any ordinary usage, the same being described hereinafter and illustrated in the accompanying drawings, in which—

Figure 1 is a vertical axial section of the front end portion of the supporting-arm, showing the bell thereof and the cap and mouthpiece therefor, together with the transmitter mechanism, which is fully described hereinafter. Figs. 2, 3, and 4 are respectively a side and front elevation and a section on line A B, Fig. 3, of the transmitter-case which is secured within the bell of the supporting-arm. Figs. 5 and 6 are respectively a side and an end elevation of an electrode and the means by which it is attached to but insulated from the case shown in Figs. 2, 3, and 4. Figs. 7, 8, and 9 show, respectively, a side and front elevation and a section on line C D, Fig. 8, of a cup-shaped electrode which is attached to the central portion of the transmitter-diaphragm and disposed in opposition to the electrode shown in Figs. 5 and 6. Figs. 10 and 11 are respectively side and edge elevations of a compound circular spring for holding the transmitter-diaphragm in yielding contact and electrical connection with a peripheral seat in the transmitter-case. Fig. 12 is a front elevation of the transmitter-diaphragm, showing central hole for attachment of the electrode illustrated in Figs. 7, 8, and 9. Figs. 13 and 14 are respectively side and edge elevations of a hollow cylinder of felt which serves as a packing for the granulated-carbon chamber and a resilient means for holding the hereinbefore-mentioned electrodes in the proper yielding position.

Similar numerals indicate like parts throughout the several views.

The arm or support 1 in this instance is hollow and is usually pivotally attached to some stationary object at the opposite end portion from the transmitter and not shown in the drawings. At the free end of arm 1 is a bell-shaped portion 2, which is externally screw-threaded to receive an internally-screw-threaded cap 3, to which the mouthpiece is secured.

The metal transmitter-case 4 is provided with an axial cylindrical portion having a hole at 5, which is filled with insulating material 6, into which latter is secured a metal electrode 7, upon whose inner end within case 4 is attached, in this instance, a carbon face 8. The interspace around this electrode, between it and the inside walls of the case 4, is filled with a felt packing 9, Figs. 1, 13, and 14, and in contact with the outer end of this packing is the rim of a cup-shaped, in this instance carbon, electrode 11, which is secured to the center of transmitter-diaphragm 10, as seen in Fig. 1, the diaphragm having a portion of its peripheral margin in contact and electrical connection with the shoulder 12 around the inside peripheral portion of case 4.

Closely adjacent to the transmitter-diaphragm, but with the main body portion in contact with the inside surface of cap 3, is a compound spring 13, having several resilient arms 14, which contact the peripheral portion of diaphragm 10 and hold it yieldingly in position. Since the periphery of case 4 is screw-threaded, it may be screwed into some desired position, so that the spring-arms 14 have the proper pressure upon diaphragm 10 and the electrode 11 be also held in position, as shown in Fig. 1, with the front annular edge in contact with the packing of felt 9, preferably between its outer and inner edges, to form between the inner surface of the bottom and sides of electrode 11 and the surface of the sides and end of electrode 8 an interspace, which is filled almost full of granular carbon 15. The inner wall of the cup is straight and parallel with the exterior of the electrode 8, so that the loose carbon 15 cannot wedge be-

tween them, and thereby interfere with the free vibration of the diaphragm, and the exterior wall of the cup is preferably beveled or inclined to form the edge very thin, which will retain the carbon, but will give the least possible surface to bear against the packing 9, which encircles the electrode 8, thereby reducing the pressure to be overcome to a minimum in forcing the cup inward when the dia-

phragm is vibrated.

A wire 16 is secured to the rear end of electrode 7, which, with the carbon facing 8 thereon, forms one electrode, and another wire 17 is attached to the transmitter-case 4, which is in electrical communication by contact with metal diaphragm 10, to which the opposite electrode 11 is attached, so that wires 16 and 17 form part of an electric circuit in which is included, in this instance, an electric battery and the primary of an induction-coil, the secondary of the latter being connected with a telephone-receiver, all of which latter-described parts are not shown.

I claim as my invention—

1. In a telephone-transmitter, a case, a diaphragm, two electrodes in the case, one of which is stationary and the other one is cup-shaped and secured to the diaphragm with its cup surrounding the stationary electrode with an interspace therebetween, a packing surrounding the stationary electrode with its inner edge engaging therewith and its outer surface engaging the edge of the cup, and granular material within the space between the electrodes for the purpose stated.

2. In a telephone-transmitter, a perforated case, a diaphragm opposite the perforation, two electrodes, one of which is stationary and projects through the perforation and the other one is cup-shaped and secured to the diaphragm with its cup surrounding the inner end of the stationary electrode and forming an interspace therebetween, a ring of packing material surrounding the stationary electrode and in engagement therewith, one face of the ring engaging the case and the other face engaging the edge of the cup, said edge being intermediate the outer and inner edges of the ring, means for holding said edge in constant contact with said surface, and granular material within the space between the electrodes, for the purpose stated.

3. In a telephone-transmitter a casing comprising side and end walls, an electrode insulatingly disposed through the end wall and terminating in a body of carbon within the casing, a fibrous ring around and in contact with the electrode, a diaphragm consisting of a disk of thin material and having the marginal edges in contact with the casing and concentric with the electrode, a cup-shaped electrode secured at the center of the diaphragm, and the open end thereof partially inclosing the first-named electrode and in contact with the fibrous material, and a partial filling of granulated carbon between the electrodes, for the purpose stated.

4. In a telephone-transmitter, a case, an electrode therein, a packing encircling the electrode, a diaphragm, a cup-shaped electrode on the diaphragm, the interior of which is of a greater diameter than the other electrode with its internal wall parallel with the sides of said other electrode, and the external wall inclined to form a thin edge, said edge being in contact with the first-mentioned electrode.

5. In a telephone-transmitter, a perforated case provided with a cylindrical portion, an annular packing in said portion, an electrode having a projection extending through the perforation and the packing, a diaphragm for the case, a cup-like electrode secured thereto and partially inclosing the other electrode and engaging with the packing with its rim, and granular material in the interspace between the electrodes.

6. In a telephone-transmitter, a case, the periphery of which is screw-threaded, an electrode in the case, an annular packing around the electrode, a diaphragm for the case, a cup-like electrode secured thereto and partially inclosing the other electrode and engaging with the packing, granular material between the electrodes, an internally-screw-threaded cap on the case, and a compound spring between the cap and the case and provided with resilient arms, for the purpose stated.

In testimony whereof I have signed my name to this specification in the presence of two subscribing witnesses.

JOHN ERICKSON.
